US00D653734S

(12) **United States Design Patent**
Sisk

(10) **Patent No.:** **US D653,734 S**
(45) **Date of Patent:** **** Feb. 7, 2012**

(54) **SCREENED GASKET**

(75) Inventor: **David E. Sisk**, Bonne Terre, MO (US)

(73) Assignee: **Bulk Tank, Inc.**, Park Hills, MO (US)

(**) Term: **14 Years**

(21) Appl. No.: **29/353,447**

(22) Filed: **Jan. 8, 2010**

(51) LOC (9) Cl. **23-01**

(52) U.S. Cl. **D23/269**

(58) **Field of Classification Search** D23/259-269;
4/252.4, 252.5, 252.6; 277/606; D7/591;
D9/905; 241/168-169, 169.2, 273.1-273.4,
241/286; 222/480, 142.1-142.9
